UNITED STATES PATENT OFFICE.

OSCAR McDONALD, OF JERSEY CITY, NEW JERSEY.

DESIGN FOR A TOY.

SPECIFICATION forming part of Design No. 27,279, dated June 29, 1897.

Application filed March 13, 1897. Serial No. 627,434. Term of patent 3½ years.

To all whom it may concern:

Be it known that I, OSCAR McDONALD, of Jersey City, in the county of Hudson and State of New Jersey, have invented and produced a new and original Design for a Toy, of which the following is a full, clear, and exact description.

Reference is to be had to the accompanying drawings, forming a part of this specification, in which toys are represented embodying my new design.

Figure 1 is an elevation of a toy embodying my design, and Fig. 2 is a cross-section on the line 3 3 of Fig. 1.

The design in its entirety is as follows: An elongate member A appears, and extending therefrom at one side is a loop B. At one

side of the loop a ring appears, with the member A extending across it, this ring being shown double and indicated by the letter C. 20 Also, at the opposite end a second ring D is shown.

The leading feature of my design resides in the elongate member having a loop at one side and a ring beyond the loop, the elongate 25 member extending across said ring.

I claim—

The design for a toy herein shown and described.

OSCAR McDONALD.
